(57) **CLAIM**

The ornamental design for a mask and gaiter combination as shown and described.

DESCRIPTION

FIG. 1 is a front view of a mask and gaiter combination showing my new design;

FIG. 2 is a rear view of the mask and gaiter combination; FIG. 3 is a right side view of the mask and gaiter combination;

FIG. 4 is a left side view of the mask and gaiter combination;

FIG. 5 is a top view of the mask and gaiter combination;

FIG. 6 is a bottom view of the mask and gaiter combination; and,

FIG. 7 is an exploded top front side perspective view of the mask and gaiter combination.

The broken lines within the claimed surfaces of the mask and gaiter combination depict claimed stitching. The broken lines and unshaded surfaces within the openings of the mask and gaiter combination define portions of the article that form no part of the claimed design. The cross-hatching lines in the drawings depict shading applied to the surfaces of the mask and gaiter combination and do not reflect a particular surface ornamentation or material.
